UNITED STATES PATENT OFFICE.

FREDERICK W. OLIVE, OF ST. LOUIS, MISSOURI, ASSIGNOR TO JOSEPH LIPIC, OF ST. LOUIS, MISSOURI.

FOUNTAIN-PEN.

1,207,317.

Specification of Letters Patent.

Patented Dec. 5, 1916.

Application filed June 12, 1914. Serial No. 844,643.

To all whom it may concern:

Be it known that I, FREDERICK W. OLIVE, a citizen of the United States of America, a resident of the city of St. Louis, State of Missouri, have invented certain new and useful Improvements in Fountain-Pens, of which the following is a full, clear, and exact description, reference being had to the accompanying drawings, forming a part of the specification.

My invention relates to a fountain pen the object being to provide a very simple, efficient and inexpensive self-filling fountain pen provided with a presser bar, and a presser finger for operating said presser bar so as to compress a collapsible ink well, and the novelty lies in certain new details of construction including a spring associated with said presser finger and presser bar.

Figure I is a side elevation of my self-filling fountain pen. Fig. II is a longitudinal section showing the collapsible ink well filled with ink. Fig. III is an enlarged longitudinal section, partly broken away, showing the collapsible ink well in its deflated position. Fig. IV is an inverted plan view of the presser bar and the spring for connecting the presser finger to said presser bar. Fig. V is a vertical section showing the presser bar, the presser finger and the spring connecting said parts.

1 designates the pen or pen point secured to a casing or pen holder A. A plug 2, forming part of the casing A is provided with a duct 3 leading to the pen 1. A collapsible ink well 4, preferably in the form of a rubber bag, is secured to the plug 2 so as to communicate with the duct 3.

5 is an elongated presser bar arranged within the casing A and associated with the collapsible ink well 4. A presser finger 6 arranged in an opening 7 in the casing A is connected to the presser bar 5 by means of a leaf spring 8 located beneath and attached at one end to the presser bar. The presser bar 5 is preferably punched to produce tongues 9 which extend through the spring 8 and serve as rivets for securing said spring to the presser bar. The free end portion of the spring 8 is preferably cut and bent outwardly to provide a pivot ear 10 which extends through a slot 11 in the presser bar 5. The inner end portion of the presser finger 6 straddles the pivot ear 10 and is connected

thereto by a pivot pin 12. The connecting spring 8 tends to pull the presser finger into engagement with the presser bar, and when the finger occupies the position shown in dotted lines Fig. II and in full lines Fig. III, the connecting spring 8 forces the flat end face of the presser finger into engagement with the presser bar 5, thereby holding the presser finger at a right angle to the presser bar. When the presser finger is folded to its normal position, shown in full lines Figs. I and II, the connecting spring 8 forces the flat inner face of the finger into engagement with the presser bar so as to retain the finger in its normal position. The free end of the presser finger is preferably beveled to produce a point 13 which overlies a notch 14 in the casing A when the finger occupies the position shown in Fig. I.

In filling the collapsible ink well 4, the operator engages the free ends of the presser finger 6 by inserting the end of one of his fingers into the notch 14, and after moving the presser finger 6 to the position shown in dotted lines Fig. II, the presser finger and presser bar are moved to the position shown in Fig. III. The collapsible ink well is thus deflated, and by dipping the pen 1 into the ink supply and permitting the collapsible ink well to expand, the ink will be drawn through the duct 3 and into the well 4. After filling the well 4 the presser finger 6 is restored to the position shown in full lines Figs. I and II.

I claim:

1. A fountain pen comprising a casing provided with a discharge duct and having an opening in its wall, a collapsible ink well in said casing communicating with said duct, a presser bar seated against said collapsible well, a presser finger slidably transversely of the casing in the opening in the wall of said casing, and a spring attached to said presser bar and to which the said presser finger is pivoted intermediate the ends of the said spring holding the inner end of the presser finger in engagement with said presser bar when the presser finger is arranged at a right angle to the presser bar, whereby the presser finger is held from pivotal movement during inward movement thereof to operate said presser bar.

2. A fountain pen comprising a casing provided with a discharge duct and having

- 2
- an opening in its wall, a collapsible ink well in said casing communicating with said duct, a presser bar seated against said collapsible well, a presser finger operable through the opening in the wall of said casing, and a spring attached to said presser bar at its side next said collapsible well and having a member extending through the presser bar, the said presser finger being pivoted to said spring member to be held against the presser bar by the spring.
3. A fountain pen comprising a pen, a casing having a duct leading to said pen, a collapsible ink well in said casing communicating with said duct, a presser bar in said casing, a leaf spring fitted to the inner face of said presser bar, the presser bar being punched to provide tongues serving as rivets for connecting the presser bar to said spring, and the free end of said spring being cut and bent outwardly to provide a pivot ear which extends through said presser bar, a presser finger straddling said pivot ear and provided with a flat end face adapted to engage the outer face of said presser bar, and a pivot pin connecting said pivot ear to said presser finger.
4. In combination with a fountain pen casing having a slot therein, of a compressor-bar movable laterally in said casing, a lever movable in said slot, a spring mounted on one face of said bar and having means connected with the lever on the other face of the bar.
5. In combination with a fountain pen casing having a slot therein, of a compressor-bar movable laterally in said casing, a lever movable in said slot, a resilient strip secured at one end to the inner face of said bar and having means at its other end extending to the outer face of said bar, said means being pivotally connected with one end of the lever.
6. In combination with a fountain pen casing having a slot therein, of a compressor-bar movable laterally in said casing, a lever movable in said slot, a resilient strip secured at one end to the inner face of said bar and having a laterally extending lug projecting beyond the other face of said bar and connected with said lever.
7. In combination with a fountain pen casing having a slot therein, of a compressor-bar movable laterally in said casing, a lever movable in said slot, a spring mounted on one face of said bar, a lug carried by said spring and extending beyond the other face of said bar and connected with said lever.
8. In combination with a fountain pen casing having a slot therein, of a lever movable in said slot, a compressor-bar movable laterally in said casing and having an opening therein intermediate of its ends, a spring on the inner face of said bar, a lug carried by said spring and extending through the slot in said bar and pivoted to said lever.
9. In combination with a fountain pen casing having a slot therein, of a lever movable in said slot, a compressor-bar movable laterally in said casing and having an opening therein intermediate of its ends, a spring on the inner face of said bar, a lug carried by said spring and extending through the slot in said bar, one end of said lever being bifurcated to receive said lug and pivotally connected therewith.

FREDERICK W. OLIVE.
